Richard M. Somers, West Orange, N. J., assignor
to Thomas A. Edison, Incorporated, West
Orange, N. J., a corporation of New Jersey

Application October 8, 1947, Serial No. 141,810

Term of patent 14 years

(Cl. D52—1)

To all whom it may concern:

Be it known that I, Richard M. Somers, a citizen of the United States, residing at West Orange, in the county of Essex and State of New Jersey, have invented a new, original, and ornamental Design for an Index Slip for Dictating Machines, of which the following is a specification, reference being had to the accompanying drawings, forming a part thereof.

Figure 1 is a plan view of an index slip for dictating machines, showing my new design; and Figure 2 is an edge view of this index slip.

I claim:

The ornamental design for an index slip for dictating machines, as shown.

RICHARD M. SOMERS.
